UNITED STATES PATENT OFFICE.

CHARLES C. SPENGLER, OF ROCKFORD, ILLINOIS, ASSIGNOR TO AUTOMATIC PENCIL SHARPENER COMPANY, OF NEW YORK, N. Y., A CORPORATION OF NEW YORK.

PENCIL-SHARPENER.

No. 889,056.

Specification of Letters Patent. Patented May 26, 1908.

Application filed February 13, 1907. Serial No. 357,151.

To all whom it may concern:

Be it known that I, CHARLES C. SPENGLER, a citizen of the United States, residing at Rockford, in the county of Winnebago and State of Illinois, have invented certain new and useful Improvements in Pencil-Sharpeners, of which the following is a specification.

One of the objects of this invention is the production of a machine for sharpening pencils arranged to sharpen or whittle the pencil by means of a diagonal or draw-cut.

Another object of the invention is the production of means for permitting the cutting member to yield in order to prevent breakage.

The invention also relates to the other improvements in pencil sharpeners hereinafter set forth.

In the accompanying drawings, Figure 1 is a front elevation partly in section of a pencil sharpener embodying the features of my invention. Fig. 2 is a vertical sectional view through the machine, taken on the plane of dotted line 2-2 of Fig. 1. Fig. 3 is a vertical section on dotted line 3-3 of Fig. 1.

The present embodiment of my invention comprises a box-like base 1 adapted to support the mechanisms of the machine, and having an opening 2 in its upper wall through which the shavings and dust produced in the operation of the machine fall into a drawer 3 slidably mounted in said base. To the upper side of the base 1 is secured a casting which provides support for the operating mechanisms. Said casting comprises a substantially circular, vertically-extending disk 4, upon the forward side of which is mounted a cutting element, to be hereinafter more specifically described, adapted to operate upon a pencil supported in a plane inclined with relation to the plane of action of said cutting element. The pencil is supported in a cylindrical opening 5 formed in the disk 4 and in a boss 6 upon the rear side of said disk. The lower end of the opening 5 terminates in the face of the disk 4 and is somewhat contracted to form a seat 7 for the point of the pencil when the latter has been fully sharpened, as will appear hereinafter. At the upper end of the opening 5 is located means for engaging the pencil to permit of said pencil being rotated, said means, in this instance, comprising a sleeve 8 rotatably mounted in the enlarged upper end 9 of the

opening 5, the lower end of said sleeve bearing upon the annular shoulder 10.

In the upper portion of the sleeve 8 is located means for yieldingly gripping the pencil being operated upon, said means comprising a plurality of spring fingers 11 attached at 60 one end to the periphery of said sleeve, one end 12 of each of said spring fingers being bent to enter a slot 13 formed in the sleeve 8, said bent portion extending into the central bore of the sleeve into position to engage a 65 pencil therein. The body portions of the spring fingers 11 lie within an annular groove 14 formed in the periphery of the sleeve. To the sleeve 8 is fixed a ring 15 provided with a peripheral series of teeth 16, said ring lying 70 upon the upper surface of the boss 6 and being frictionally held thereagainst by means of two spring fingers 17 bearing upon the upper surface of said ring, said fingers being provided with an attaching portion 18 secured to the rear side of the boss 6. The spring fingers 17 frictionally engage the ring 15 with sufficient force to prevent the sleeve 8 and the pencil rotated thereby from rotating too freely. The teeth 16 of the ring 15 75 project beyond the face of the disk 4 into position to be engaged by a member hereinafter described by means of which the sleeve 8 is given a succession of intermittent partial-rotations.

Upon the rear side of the disk 4 is a bearing 19. A shaft 20 is rotatably mounted in said bearing and carries at its forward end a crank or face plate 21 which may be formed integral with said shaft, if desired, said face 90 plate lying within a circular recess 22 formed in the disk 4. To the rear end of the shaft 20 is fixed a crank 23.

A knife bar 24 having an elongated opening 25 therein is slidably and pivotally connected with the disk 4 by means of a screw 26 or equivalent device extending through said elongated opening and engaging the disk 4. At a suitable point in its length the knife arm 24 is pivotally connected with the face plate 100 21 by means of the wrist pin 27. A knife blade 28 is secured to the end of the knife arm 24 which extends toward the opening 5 in the disk 4. The cutting element is preferably made separate from the knife arm, as 105 just described, in order that it may be removed when desirable for sharpening or renewal. In the present instance, the knife

blade 28 is secured to the knife arm 24 by means of pins 29 fixed in the knife arm and entering openings in the knife blade, and a screw 30 extending through said knife blade into a screw-threaded opening in the knife arm.

A finger 31 is fixed to the knife arm 24 at a suitable point and is of sufficient length to enter the space between two adjacent teeth 16 of the ring 15 when said knife arm is at the highest point in its movement. As the knife arm 24 moves forwardly and downwardly, said finger pushes before it a tooth 16, thereby rotating the sleeve 8 and the pencil lying within said sleeve.

In order to permit the knife blade 28 and the knife arm 24 to yield slightly so as to prevent breakage should a pencil be forced into the lower end of the opening 5 while said 20 knife blade lies over said opening, I make the shaft 20 slideable longitudinally in its bearing 19 and provide a coiled spring 32 for holding said shaft and the cutting element attached to and actuated by said shaft in their normal 25 position. Said spring surrounds the shaft 20 and lies within a recess 33 formed in the rear end of the bearing 19, the spring bearing against the inner end of said recess and the crank 23.

30 In operation, the pencil to be sharpened is inserted in the sleeve 8 and the opening 5, the spring fingers 11 yielding to permit the pencil to pass between them, but frictionally engaging said pencil. The lower portion of 35 the pencil projects to a greater or less extent through the lower end of the opening 5. The shaft 20 being rotated by means of the crank 23, the knife arm 24 is reciprocated and tilted, causing the knife blade 28 to move 40 diagonally downward and across the lower end of the opening 5, and thereby cut off a portion of the wood and lead of said pencil projecting from said opening. During each 45 complete cycle of movement of the knife arm 24 the finger 31 carried by said knife arm engages the teeth 16 of the ring 15, causing a partial rotation of the sleeve 8 and the pencil, and thereby causing a fresh portion 50 of the pencil to be presented to the knife. As the pencil is whittled away the downward pull of the knife blade upon the pencil causes the latter to sink deeper into the opening 5 until the point reaches the bottom of the seat or recess 7, when further 55 descent is prevented, the pencil then being fully sharpened. It will be observed that the movement of the knife blade 28 is diagonally downward over the lower open end of the opening 5, thus causing a diagonal or 60 draw-cutting action upon the pencil. Such a draw-cutting action is less likely to splinter the wood of the pencil or break the lead thereof than a cut longitudinally of the pencil or at right angles thereto. Should the 65 pencil be forced into the opening 5 when the

knife blade 28 stands in front of said opening, the coiled spring 32 permits said knife blade to yield outwardly, thus preventing breakage.

While I have described in some detail a specific embodiment of my invention which I deem to be new and advantageous in the details of construction, I do not desire to be understood as limiting myself in respect to the broader features of my invention to the specific construction shown and described.

I claim as my invention:

1. In a pencil sharpener, in combination, means for rotatably supporting the pencil; a slidably and tiltably mounted knife bar; means for moving said knife bar; and means carried by said knife bar adapted to rotate said pencil-supporting means.

2. In a pencil sharpener, in combination, means for rotatably supporting the pencil; a toothed member fixed to said pencil-supporting means; a slidably and tiltably mounted knife bar; means for moving said knife bar; and a member carried by said knife bar adapted to engage said toothed member.

3. In a pencil sharpener, in combination, a rotatably mounted sleeve for supporting the pencil; an annular toothed member fixed to said sleeve; a slidably and tiltably mounted knife bar; means for moving said knife bar; and a finger fixed to said knife bar and adapted to engage said toothed member.

4. In a pencil sharpener, in combination, means for rotatably supporting the pencil; a knife bar; means engaging one portion of said knife bar to permit of a sliding movement thereof; means for giving another portion of said knife bar an orbital movement; and means carried by said knife bar for rotating said pencil-supporting means.

5. In a pencil sharpener, in combination, means for rotatably supporting the pencil; a knife bar; means engaging one portion of said knife bar to permit of a sliding movement thereof; a crank operatively attached to said knife bar; and a member attached to said knife bar adapted to rotate said pencil-supporting means.

6. In a pencil sharpener, in combination, means for rotatably supporting the pencil; a knife bar having an elongated opening therein; means extending through said opening for limiting the movement of said knife bar; a crank attached to said knife bar; and a member carried by said knife bar adapted to rotate said pencil-supporting means.

7. In a pencil sharpener, in combination, means for supporting the pencil; a fixed member; a knife bar having a longitudinal opening therein; a member extending through said longitudinal opening and attached to said fixed member; a cutting element attached to said knife bar; and a crank connected with said knife bar at a point be-

tween said cutting element and said slotted portion.

8. In a pencil sharpener, in combination, a member having an opening therein for the reception of the pencil, said opening extending to a plane surface of said member; a cutting element; and means for actuating said cutting element comprising a longitudinally slidable, spring-held shaft adapted to hold 10 said cutting element yieldingly against said plane surface.

9. In a pencil sharpener, in combination, a member for supporting the pencil, said member having an opening therein through which 15 the pencil may project; a cutting element arranged normally to move over said opening in a plane inclined with reference to the plane in which the pencil is supported, said cutting element being arranged to yield laterally away from said opening; and means 20 tending to hold said cutting element in operative relation to said opening.

10. In a pencil sharpener, in combination, a member for supporting the pencil, said 25 member having a plane surface through which the pencil projects, said surface lying in a plane inclined with reference to the pencil; a cutting element arranged normally to move in contact with said surface, said cutting element being arranged to yield laterally away from said surface; and means 30 tending to hold said cutting element against said surface.

11. In a pencil sharpener, in combination, 35 a member having an opening therein for the reception of the pencil; a slidably and tiltably mounted knife bar carrying a knife; means for moving said knife bar; and means for yieldingly pressing said knife against said member.

12. In a pencil sharpener, in combination, 40 a member for supporting the pencil, said member having a plane surface through which the pencil projects, said surface lying in a plane inclined with reference to the pen-

cil; a slidably and tiltably mounted knife bar; a cutting element carried by said knife bar and arranged normally to move in contact with said surface, said knife bar being arranged to yield laterally; and means tending to hold said cutting element against said surface. 50

13. In a pencil sharpener, in combination, a supporting member having an opening therein for the reception of the pencil, said 55 opening extending to a plane surface of said supporting member; a sleeve rotatably mounted in said supporting member and adapted to receive the pencil; means carried by said sleeve for engaging the pencil; 60 an annular toothed member fixed to said sleeve; a shaft rotatably mounted in said supporting member; a crank attached to said shaft; a knife bar connected to said crank, said knife bar having an elongated 65 opening therein; a member fixed to said supporting member and extending into said elongated opening; a knife fixed to said knife bar in position to operate across the opening in said supporting member; a coiled 70 spring surrounding said shaft and bearing at its end against said supporting member and a portion fixed with relation to said shaft for yieldingly holding said knife against said plane surface; and a finger fixed to said knife 75 bar and adapted to engage said annular member for rotating said sleeve.

14. In a pencil sharpener, the combination of a pencil-holder provided with an opening in one face, through which a portion of the 80 pencil is adapted to protrude, a cutter movable adjacent the face of the holder, a supporting member for the cutter, means for moving the member to operate the cutter, and yielding means for holding the cutter in 85 position with relation to the pencil holder.
